SMELTING APPARATUS

John Hedley Grace, Vancouver, British Columbia, Canada, assignor to Ronald H. Grace, Vancouver, British Columbia, Canada

Application April 2, 1942, Serial No. 437,447

2 Claims. (Cl. 13—1)

This invention relates to improvements in furnaces for smelting ores and particularly iron ores.

An object of the present invention is the provision of a furnace for smelting ores and particularly iron ores, in places where coking coal is not readily available and is, therefore, so expensive that it makes the cost of smelting prohibitive.

Another object is the provision of a smelting furnace for ores in which non-coking coal, such as low grade bituminous or lignite coal, or petroleum oil or other cheap carboniferous material, may be used.

A further object is the provision of a smelting furnace for ores by means of which the cost of producing iron and other metals, and particularly steel, is considerably reduced.

A further object is the provision of a smelting furnace for iron ore in which the same heat is used for reducing the ore, and refining and alloying the iron to any desired steel product.

Another object has been to design a smelting furnace whereby liquid, gaseous, or powdered fuel may be used in combination with electrical energy, thereby conserving to a great extent the consumption of electrical current and thus effecting a great economy in operation.

Still another object has been to design a smelting furnace wherein heat losses are reduced to the minimum while charging and alloying, and offering greater facility of operation than usual in furnaces of this kind.

With the above and other objects in view, the present invention consists of smelting apparatus comprising a horizontally-inclined rotatable kiln, means for rotating the kiln, means for supplying charged ore to the kiln at the upper end thereof, means for directing hot reducing gases through the kiln, and an electric furnace connected to the lower discharge end of the kiln, said furnace receiving the reduced materials from the kiln for refining, as more fully described in the following specification and illustrated in the accompanying drawings, in which

Figure 1 is a side elevation, partly in section, of the smelting apparatus,

Figure 2 is a sectional view taken on the line 2—2 of Figure 1,

Figure 3 is a reduced elevation of the apparatus.

Referring more particularly to the drawings, 10 is a horizontally-inclined, open-ended kiln rotatably mounted in any suitable manner, such as by means of bearings 11 carried by a platform 12 mounted on legs 13. The kiln is rotated in

any desired manner, such as by a motor 14 driving a gear 15 which meshes with a ring gear 16 mounted on said kiln. The kiln has an enlargement 17 adjacent its lower end.

A hopper 18 is mounted adjacent the upper or feed end of the kiln and a feed pipe 20 extends downwardly from the hopper and extends into the end of the kiln. Dust catchers and gas scrubbers 21 of well known construction, are directly connected at one end to the feed end of the kiln by means of a stuffing box 22 which is packed with asbestos material, and at their opposite end to an exhaust fan 23 having a discharge pipe 24 which extends to storage tanks (not shown).

The discharge or lower end of the kiln 10 extends into a vertical charging shaft 25 at a point spaced from the top thereof. A water jacket 26 is provided around the kiln at the point of junction with the shaft 25 and suitable means is provided for forming a fluid-tight joint at 27.

A charging hopper 28 projects into the upper end of the shaft 25, said hopper being provided with a valve 30. An electric furnace 31 is connected to the lower end of the shaft 25. This furnace may be of any desired type, such as, for example, a circular tilting furnace, as shown, of the three phase resistance type, having three or six standardized electrodes 32, each extending through a water jacket 33 mounted on the top of the furnace. When a tilting furnace is used, a gas-tight water jacketed joint 34 is provided at the lower end of the shaft, in order to allow the furnace to be tilted for pouring the slag and metal. The electric furnace is provided with a slag hole 35 and a tap hole 36.

A combustion and mixing chamber 37 is mounted on the shaft 25 opposite the kiln 10 and this chamber gradually narrows down to a restricted outlet opening 38 in line with said kiln. This chamber may be designed to burn powdered coal, gas or, as shown, oil. In the latter case a pipe 40 connected to an oil reservoir (not shown) is adapted to supply oil to the chamber while another pipe 41 supplies a limited quantity of air thereto, there being only sufficient air to permit incomplete combustion of the oil in the chamber. Any suitable means may be provided for regulating the flow of oil and air through their respective pipes 40 and 41 although this has not been shown in the drawings for the sake of clarity. If desired, a pyrometer 42 and a thermostat 43 may be provided adjacent the outlet opening 38 of the combustion chamber. The thermostat may be connected to the control valves of the pipes 40 and 41 in any known manner, in order to con-

trol these valves in accordance with the temperature of the gases at the outlet of the chamber.

The kiln 10, shaft 25, electric furnace 31, and combustion chamber 37 are lined with a suitable refractory material.

A pipe 44 having a gas pump 45 therein extends from the dust catcher 21 to a point adjacent the pyrometer 42 where it terminates in a nozzle 46.

The operation of this apparatus is as follows:

Oil from the pipe 40 is mixed with a limited supply of air from the pipe 41 and burned in the combustion chamber 37 which is so shaped that the products of combustion or gases are thoroughly mixed before passing through the restricted opening 38 into the kiln 10. The whole 15 apparatus is kept air-tight and the limitation of the quantity of air supplied to the combustion chamber ensures the formation of carbon monoxide therein. Thus a proper reducing atmosphere is maintained throughout the kiln.

The hopper 18 is maintained full of crushed iron ore, a suitable flux, such as limestone, and a reducing agent consisting of fine coal, or petroleum oil, or other carboniferous material, all in their proper proportions as commonly used in this type of work. This mixture is termed "charged ore" herein and in the annexed claims. The charged ore which is preferably crushed to pass through a quarter inch mesh, is fed from the hopper through the feed pipe 20 into the kiln 10 which is slowly rotating. As the kiln rotates it automatically removes a certain proportion of the charge from the hopper and the charged ore progresses slowly along the inclined kiln towards the shaft 25. During the earlier part of the progress of the charge along the kiln the volatile constituents of the charge are driven off and the coal forming the reducing agent is carbonized at a low temperature. As the charge moves, it is subjected to a continuous increase in temperature, derived from the hot reducing gases from the combustion chamber, which pass in the opposite direction to the progress of the charge. The duration of the charge in the kiln must be sufficiently long to allow full reduction of the iron oxide to metallic iron. Crushing of all materials to small particles permits of rapid heat penetration and chemical reaction.

The design of the combustion chamber 37 assures a thorough mixing of the gases therein and permits a reducing atmosphere being maintained throughout the kiln and prevents any free oxygen entering therein and reoxidizing the already reduced ore. The thermostat 43, owing to its control of the supply of oil and air to the combustion chamber, automatically regulates the constituents of combustion in the chamber, thereby controlling the temperature in the kiln and keeping it at a predetermined temperature, so as to assure the most rapid reduction and chemical reaction in the pre-heating and reducing zones, while avoiding the overheating of the charged ore in the kiln, which would cause it to become plastic and stick to the wall of the kiln and block the passageway thereof.

The sponge iron, with the other materials of the charge in a loose, disintegrated condition, and retaining its heat, is discharged from the kiln directly and continuously into the shaft 25 and falls directly into the electric furnace 31. It retains the loose, separate character of its particles during its fall down the shaft. The charge in this condition and at an approximate temperature of 1000 degrees centigrade is then subjected to the heat from the electric arc, where

it is melted. When sufficient metal has collected, the slag is run off through the slag hole 35. The molten iron may be refined, and the slag made basic or acid as desired to remove any objectionable elements in the iron, by charging the necessary material through the hopper 28 at the top of the shaft. When the molten iron is sufficiently refined, any desired grade of pig iron may be made by charging through the hopper 28 the necessary alloy.

If desired, the refining and alloying may be done in separate electrical furnaces so as not to interfere with the continuous action of the apparatus.

During the period of refining and alloying, the rotating kiln and the exhaust fan 23 are stopped, the gases from the electric furnace escaping through the hopper at the top of the shaft. The gases which pass through the rotating kiln in large volume are rich in carbon monoxide, owing to the fact that the oil in the combustion chamber is not fully combusted and the excess carbon in the charge maintains a reducing atmosphere in the kiln.

After the gases from the kiln have passed through the dust catchers and gas scrubbers 21, they may be stored and used for any desired purpose.

Some of the gases are pumped from the dust catchers through the pipe 44 by the pump 45 to the nozzle 46 where they are burned continuously. The flame at the nozzle acts as a gauge to indicate the condition of the gas passing through the kiln. Carbon monoxide is necessary for the proper chemical action in the kiln and if too much air is admitted to the combustion chamber 37 or if any air gets into the apparatus, the gas is converted to carbon dioxide in the kiln which will re-oxidize the iron. If carbon monoxide passes through the pipe 44, the flame is high but if carbon dioxide reaches the nozzle 46, the flame is low and spluttering, thus indicating the character of the gas in the kiln.

This apparatus permits the use of petroleum oil, both as a reducing and heating agent, for the preheating of the charge and the reducing of the iron ore while in the rotating kiln, or non-coking coal may be used both as heating and reducing agent for the charge in the kiln; but it is to be understood that in the electric furnace 31 the sole heating agent is electric energy only.

The large volume of gases that pass through the rotating kiln are rich in carbon monoxide, and may be used under steam boilers or for other commercial purposes.

By fully reducing the iron ore and preheating the charge in the kiln, by a separate and comparatively cheap heating agent, such as powdered coal or fuel oil, a great economy is gained, in saving a large amount of electric energy that otherwise would be necessary for the melting of the charge in the furnace.

Various modifications may be made in this invention without departing from the spirit thereof or the scope of the claims, and therefore, the exact form shown is to be taken as illustrative only and not in a limiting sense, and it is desired that only such limitations shall be placed thereon as are disclosed in the prior art or are set forth in the accompanying claims.

What I claim as my invention is:

1. Smelting apparatus comprising a horizontally-inclined rotatable kiln, means for supplying charged ore to the upper end of the kiln, a charging shaft at the lower end of the kiln, said kiln

opening into the shaft adjacent the top thereof, a combustion and mixing chamber having a restricted opening which communicates with the shaft, means for supplying fuel to the chamber, means for supplying a limited amount of air to the chamber, the incomplete combustion of the fuel in the chamber producing a reducing atmosphere for the kiln, an electric furnace connected to the lower end of the shaft to receive the reduced ore from the kiln, said reduced ore being melted in the furnace, and an exhaust fan connected to the upper end of the kiln adapted to draw heat from the furnace and the reducing atmosphere through the kiln.

2. Smelting apparatus comprising a horizontally-inclined rotatable kiln, means for rotating the kiln, means for supplying charged ore to the upper end of the kiln, a vertical charging shaft at the lower end of the kiln, said kiln opening

into the shaft adjacent the top thereof, a combustion and mixing chamber gradually narrowing down to a restricted opening which communicates with the shaft opposite the lower end of the kiln, means for supplying fuel to the chamber, means for supplying a limited amount of air to the chamber, means for controlling the fuel and air supply to the chamber, the incomplete combustion of the fuel in the chamber producing a reducing atmosphere for the kiln, an electric furnace connected to the lower end of the shaft to receive the reduced ore from the kiln, said reduced ore being melted in the furnace, and an exhaust fan connected to the upper end of the kiln adapted to draw heat from the furnace and the reducing atmosphere through the kiln.

JOHN HEDLEY GRACE.
